COMBINED PACKAGING CONTAINER AND PITCHER

Donald M. Kitterman, 1401 Fairfax, Traffic Way,
Kansas City, Kans.

Filed Mar. 16, 1964, Ser. No. 79,029

Term of patent 14 years

(Cl. D58—5)

FIG. 1 is a perspective view of a combined packaging container and pitcher showing my new design;
FIG. 2 is a side elevational view;
FIG. 3 is a rear elevational view;
FIG. 4 is a front elevational view;
FIG. 5 is a top plan view; and
FIG. 6 is a partial sectional view through the upper portion.

I claim:

The ornamental design for a combined packaging container and pitcher as shown.
